UNITED STATES PATENT OFFICE.

MARIE LÉONA JACKSON, OF BEXHILL, ENGLAND.

REMOVABLE STIFFENER FOR THE INSIDE PORTIONS OF THE HEELS OF BOOTS AND SHOES.

Application filed October 11, 1921. Serial No. 507,111.

To all whom it may concern:

Be it known that I, MARIE LÉONA JACKSON, a subject of the King of Great Britain, residing at 2 Park Road, Bexhill-on-Sea, in the county of Sussex, England, have invented certain new and useful Improvements in Removable Stiffeners for the Inside Portions of the Heels of Boots and Shoes, of which the following is a specification.

The object of this invention is to provide a heel stiffening or supporting device which can be readily affixed to the inside of any existing boot or shoe irrespective of the size thereof, without altering the internal length of the said boot or shoe, and which device can be with equal facility removed from the said boot or shoe and applied to another boot or shoe, which may be of different size. Thus the device which is the subject of the present invention differs essentially from previously known stiffening devices which are built up in the boot or shoe in the process of manufacture.

In order that the said invention may be clearly understood and readily carried into effect, the same will now be described more fully with reference to the accompanying drawings in which:—

Figures 1 and 2 illustrate an embodiment of the invention, Figure 1 being a perspective view of one metal plate detached, and Figure 2 a plan representing two of such plates secured in position in the heel of a shoe.

The device may be made of aluminum or other suitable rustless metal, and comprises two counterpart pieces having approximately triangular bases A and B (Figure 2) with upturned flanges G having their upper edges rounded, the points or apices of the bases overlapping one another, each piece being bored with a row of holes C for relative adjustment, say four of such holes being in the row, and a fifth hole D in another part of the base of the plate to prevent swivelling. Three nails or screws E will then be required to fix the device, namely, one passing through the holes C in the two plates which are brought into register with

one another, and one through the hole D in each plate, these nails or screws being forced down into the material of which the boot heel F is made till the plates are firmly fixed with their upturned flanges G touching and following the shape of the softer material of which the "counter" of the foot wear is made.

The metal plates may be covered by heel linings made of cork linoleum or other suitable material.

The vertical walls or flanges of the device being adjusted against the internal surface of the wall of the boot or shoe contiguous to the curved or substantially erect leather stiffeners which are usually incorporated in the heel portions of footwear, or in the position usually occupied by such leather stiffeners, the said walls support the heel of the wearer at both sides and offer a firm resistance to lateral movements within the footwear, as well as resisting any tendency to lateral inclination of the foot, which would otherwise cause uneven or "lop-sided" wear of the boot or shoe where it meets the ground, and the plates being rigid will absolutely prevent the material of which the footwear is made from being bulged out by internal pressure at either side of the heel.

I claim:

1. In a device for the purpose specified, two counterpart members each comprising an upturned wall and a substantially horizontal base, the two base portions being of approximately triangular form and in use overlapping at the apices thereof, each base portion being bored with a marginal row of holes for the reception of fastening means common to the two members when any marginal hole in one of said base portions is placed in register with any marginal hole in the base portion of the other member, and with an additional hole for the reception of co-operating fastening means to prevent swivelling of either member relatively to the other member.

2. In a device for the purpose specified, two counterpart members of rustless metal each comprising an upturned wall having thin rounded upper edges and a substan-

tially horizontal base, the two base portions being of approximately triangular form and in use overlapping at the apices thereof, each base portion being bored with a marginal row of holes for the reception of fastening means common to the two members when any marginal hole in one of said base

portions is placed in register with any marginal hole in the base portion of the other member, and with an additional hole for the reception of co-operating fastening means to prevent swivelling of either member relatively to the other member. 10

MARIE LÉONA JACKSON.
